UNITED STATES PATENT OFFICE.

ADOLF PILLICH, OF LACKAWANNA, NEW YORK.

ELECTRIC RAILWAY SIGNAL SYSTEM.

1,088,363.

Specification of Letters Patent. Patented Feb. 24, 1914.

Application filed March 23, 1910. Serial No. 551,846.

To all whom it may concern:

Be it known that I, ADOLF PILLICH, a subject of the Emperor of Austria-Hungary, residing at Lackawanna city, in the county of Erie and State of New York, have invented a new and useful Improvement in Electric Railway Signal Systems, of which the following is a specification.

This invention relates more particularly to improvements in block signaling systems which operate signals carried on the trains.

The objects of this invention are to produce a reliable and efficient train signaling system by means of which the engineer in charge of the train is notified of the presence on the same track of a preceding or of an approaching train, while his train will send similar signals to the blocks ahead and in rear; also to produce a system which does not require the rails to be bonded, connected, or divided into blocks insulated from each other, and which has no live parts exposed on the track which are liable to become connected and thus disarrange the system; also to produce a system which does not require any complicated or expensive apparatus, and in which the cost of maintenance will be low, owing to the fact that the currents which operate the signals are of short duration and therefore require very little power, and in which the apparatus is not liable to get out of order and will require very little attention; and also to improve these systems in the respects hereinafter described and set forth in the claims.

In the accompanying drawings, consisting of four sheets: Figure 1 is a diagrammatic plan of five blocks of the signal system embodying this invention, showing the electrical connections. Fig. 2 is a diagram of electrical connections for three blocks at either end of the system. Fig. 3 is a diagram of electrical connections of the circuit carried by the train and of a signal setting apparatus located on the track. Fig. 4 is a plan view of one of the circuit closing devices. Fig. 5 is a horizontal sectional plan thereof on line 5—5, Fig. 6. Fig. 6 is a central vertical section thereof. Fig. 7 is a central vertical section of one of the contact devices located on the track. Fig. 8 is a section of one of the train wheels equipped with a contact making ring. Fig. 9 shows a device carried by the train for actuating the circuit closing devices.

Like reference characters refer to like parts in the several figures.

Briefly stated, the operation of the system is as follows: By means of a series of circuit closing devices located adjacent to the track and adapted to be actuated by parts on the locomotive, circuits are closed through magnets located convenient to the blocks in which the electrical connections are to be arranged to give a signal in the engineer's cab. These magnets close switches which connect pairs of contact devices, located along the track in position to be engaged by parts on the train, to the wires which supply current to the system. When the contact making devices on the train and on the track are in engagement, current flows from the supply wires through a circuit on the train which actuates signals in the engineer's cab. By connecting different contact points to the supply wires, different signals are given to the engineer, by means of which he can tell if the track ahead of him is clear or is occupied by a preceding or by an approaching train.

A A represent the rails and B B' the supply or feeder wires, marked + and —, which carry the current that operates the system from any suitable source of current supply located at any suitable generating station, and C C' are groups of signal setting apparatus or devices located near the track, two of these groups being required for each block. The blocks can be made of any desired length, depending on the amount of traffic, but should be long enough to give the engineer time after receiving a warning, to stop his train before running into the next block. For the sake of clearness all the groups of devices C are shown in the diagram on one side of the track, while the other groups of devices C' are shown on the opposite side of the track. This arrangement, however, is not essential.

D D' represent circuit closing devices which are located adjacent to the track where they can be actuated by an arm depending from one side, for instance, the right hand side of the locomotive, as regards the direction of motion thereof, so that circuits controlled by these devices will be closed while engaged by the arm. These devices D D' and the circuits controlled by them are duplicated on both sides of the track so that the system will operate in the

same manner for trains moving in either direction.

E E' E² E³ and F F' F² F³ represent contact devices or terminals which are arranged in groups of four and are adapted to be engaged simultaneously by four coöperating contacts on the train. Two of these groups of contact devices are required for each block and may be located at the ends or between the ends of the block, as desired. As shown in the drawings, the circuit closing devices D and D' are located outside of the rails and the contact devices E E' E² E³ and F F' F² F³ between the rails, but these devices may be located anywhere on the track where they can be conveniently engaged by coöperating parts on the train.

The signal setting devices C C' may be inclosed in any suitable protecting boxes along the track or may be located in any convenient place, and each comprises four electromagnets c c' c² c³, (see Fig. 3), and two double pole switches c⁴ c⁵. These parts constitute two similar groups consisting each of two magnets and a switch, and are so arranged that when the magnets c and c² are energized, the movable parts of the switches c⁴ and c⁵, which are connected to the supply wires B and B', are pressed against switch contacts or parts c⁶ which are connected to the contact devices on the track, as will be explained later, so that the contact devices will form terminals of a circuit which is completed through a signal mechanism in the locomotive cab when the contact devices are engaged by co-acting devices on the train. These switches are normally held open by any suitable means, for instance, the springs c⁷. The magnets c and c² attract their armatures c⁸ and draw the switches c⁴ and c⁵ into contact with the switch contacts c⁶, where they are held by latches c⁹ which engage with the armatures c⁸. When the magnets c' and c³ are energized, the latches are drawn from engagement with the armatures c⁸ against the action of the springs c¹⁰, thereby permitting the switches to open and break the circuit. The means described for opening and closing the switches are preferably used, although other electrically controlled means may be employed. Only a current of short duration is required to open or close the switches, which reduces the power required to operate the system to a minimum.

The object of each of the circuit closing devices D D' is to connect electrically the three conductors terminating therein. This device may be of any suitable construction but is preferably constructed as shown in Figs. 4, 5 and 6. Each device consists of a box-shaped part or casing d in which the ends of three conductors are connected to short conductor springs d', and a cover or lid d² which is pivoted at one side of the box.

Both cover and box are preferably made of metal and must be insulated from all current carrying parts. This cover d² has an enlarged horizontal portion with a curved or cam-shaped edge d³ facing the rail with which a depending arm from the locomotive engages. The lower portion of the cover is provided on its inner side with a conducting strip d⁴ insulated from the cover, and adapted to connect electrically the conductor springs d' when moved into contact therewith. The actuating device on the locomotive moves the cover against the action of the spring d⁵ so as to press the conducting strip against the conductor springs d'. This spring d⁵ is preferably made strong enough to prevent the cover from being moved into a position in which the conductor springs are connected unless forced into that position by the actuating device on the locomotive to prevent the devices from being maliciously or accidentally actuated and the operation of the system thus interfered with.

The actuating devices or rods d⁶ d⁸ which 90 actuate the circuit closing devices D D' on the track are preferably secured at the sides of the locomotive or the tender and are preferably so connected that as one rod is lowered into position to engage with the 95 contact devices, the rod on the other side of the train is raised out of operative position with the corresponding devices on that side of the track. These rods may be shifted by any suitable means which, however, are preferably of such nature as to be actuated by the actuation of the reversing lever of the locomotive, so that the engineer cannot reverse the locomotive without placing the actuating rods in proper position for operation as required by the changed direction of motion of the train. As shown in Fig. 9, the rods d⁶ are adapted to slide vertically in guides d⁷ on the truck and are moved in opposite directions by a lever d⁸, fulcrumed at its center and connected at its opposite ends to the two actuating rods d⁶. An arm d⁹ is secured to the lever d⁸ and is connected by any suitable connecting mechanism to the reversing lever or other operating handle. 105

The contact devices E E' E² E³ and F F' F² F³ are preferably alike, as shown in Fig. 7, and each comprises a box-shaped casing f and a contact lever f' which is pivoted in the upper portion of the casing f and insulated therefrom. The contact lever is normally held out of contact with a conductor spring f² by a spring f³ which is of such strength that considerable force is required to move the lever f' into engagement with the conductor spring f². The conductor spring f² is connected by the switch c⁴ or c⁵ and suitable conductors hereinafter described to the supply wires B B' 120 of the system. The contact lever f' is nor- 125

5 mally not connected to the supply circuit and the exposed parts of the contact devices are normally dead. Hence if the exposed parts of two or more of these devices 10 become electrically connected with each other in any way, no current will flow between the connected devices from the supply lines, thus preventing short circuits and waste of current. When forced into contact with the conductor springs f^2 by contacting devices on the locomotive, the current flows from the supply lines through the springs f^2 and through the contact levers to the circuits carried on the train to 15 operate the signals in the locomotive cab.

Any suitable means carried by the train for making contact with the contact devices on the track may be used, provided that they are so arranged that the four contacts 20 on the train engage simultaneously with the four contacts on the track. A construction of one of these contact devices, which is preferably used, is shown in Fig. 8, in which G represents a conducting ring or part 25 which is secured to and insulated from the wheels g of a truck on the tender, locomotive or other part of a train. The current is conducted from this ring to a circuit on the train by means of a brush g' which is 30 mounted on a frame of the car so as to make contact with the ring at its upper portion.

The signals carried by the train, the apparatus for actuating them, and the electrical connections therefor are shown diagrammatically in Fig. 3. h h' represent 35 two electro-magnets which are located in the engineer's cab and are so arranged as to attract their armatures h^2 and draw them inwardly, thereby closing the single pole switches h^3 . The armatures are held in their inmost positions against the action of 40 springs h^4 by latches h^5 , and are adapted to be released by the engineer by raising the handles h^6 of the latches. The magnet h is connected by conductors h^7 h^8 to two diagonally opposite contact rings G G which 45 engage with the contacts F F' and the magnet h' is connected by conductors h^9 h^{10} to the other two contact rings G G which 50 engage with the contacts F^2 F^3 . As shown in Fig. 3, the train carrying the signals is supposed to be moving toward the right and the contact rings G which are carried by 55 a part of the train indicated by dotted lines, are in engagement with the contact devices F F' F^2 F^3 . Of these contacts the diagonally opposite pairs F F' are connected by 60 conductors i and i' to the contact points of the switch c^5 , the movable parts of which are connected to the positive and negative 65 lines B B' by the conductors l^2 and l . The contacts F^2 F^3 are connected by conductors i^2 and i^3 to the contact points of the switch c^4 and the movable parts of this switch are connected to the positive and negative lines

70 by the conductors l^2 and l . The switch c^4 in Fig. 3 is shown closed, hence the contacts F^2 F^3 are connected to the lines B B' and when they are engaged by the co-acting contacts G G on the train, a circuit will be completed from these contacts through conductors h^9 and h^{10} to the magnet h' , which closes the switch h^3 . Since the switch c^5 is open the contacts F F' will be disconnected from the supply line and no current will 75 flow through the magnet h which is connected with these contacts through contacts G G and conductors h^7 and h^8 . The circuits from the supply lines B B' to the contacts E E' and E^2 E^3 are connected in 80 the same manner as those described for the contacts F F' and F^2 F^3 so that signals may be actuated on the train through the former contacts in the same manner as above described. The local circuits which are carried on the train, which are closed by the switches h^3 , both receive their power from a battery k to which they are connected by conductors h' , switches h^3 , and conductors h^2 to the lamps or signal lights K and K' 85 and the bells or other alarms h^8 , and back to the battery through conductors h^4 . When any one of these local circuits is completed by the energizing of one or another of the magnets h or h' , the current will keep the 90 bell ringing and the lamp lighted until the circuit is broken by the engineer by raising the handles h^6 and thus releasing the armatures h^2 from the latches h^5 , whereupon the switches h^3 will be opened by the action of 95 springs h^4 . The lamp K is of a certain color, for example, red, and the lamp K' of another color, for instance, green. The circuit through the magnet h which will 100 actuate a switch to light the red lamp K , 105 is completed through the contact devices F F' or E E' which are connected to the supply lines by an approaching train, while the contact devices F^2 F^3 and E^2 E^3 , which 110 complete a circuit through the magnet h' , 115 which will close a switch to light the green lamp K' , are connected to the supply line by a preceding train on the same track. Thus the engineer is warned by the color of 120 the light of the presence of a train on the same track and can distinguish whether the train is preceding or approaching. The signal mechanism carried on the train as described, is simple and effective but any other circuits or signal mechanism actuated as described may be used.

Fig. 2 shows three blocks at one end of the line, the end of the line being at the left hand side of the figure. The connections for the first two blocks 1 and 2 nearest the 125 end are slightly different, while for the third block 3 they are the same as for the other five blocks, shown in Fig. 1. The diagram in Fig. 1 shows five blocks of track, 4, 5, 6, 7 and 8, equipped with this signal system, 130

the five blocks being supposedly located at least two blocks distant from either end of the line, so that all the connections of the several blocks are alike. Each block is provided with four circuit closing devices D D' and D' D', two located on each side of the track, those on one side of the track being engaged by the actuating rod d^6 of a locomotive moving in one direction, while those on the other side are actuated by trains moving in the opposite direction. For convenience it is assumed that the rod which actuates these devices depends from the right hand side of the locomotive when the train is moving forwardly. Each block except the end one has two sets of contact devices E E' E² E³ and F F' F² F³, which may be located on any part of the block, providing they are sufficiently far from the circuit closing devices D D' so that a train can actuate the device D before making connection with any of the contact devices and will be clear of the contact devices before actuating the circuit closing device D' when about to leave the block. Two sets of apparatus C C' for connecting and disconnecting contact devices to the supply lines are also required for each block except the end one, which may be located wherever convenient to the contact devices. As shown in Figs. 1, 2 and 3, the middle conductor spring of the circuit closing devices D and D' located on one side of the track, the lower side in the drawing, and one terminal of each of the switches c^4 and c^5 of the apparatus C is connected to a conductor l which leads to the negative conductor B' of the supply line. A branch l' of this conductor connects in the same manner the corresponding devices on the opposite side of the track. A conductor l^2 leads from the positive conductor B to the other contacts of the switches c^4 and c^5 and to the positive terminals of each magnet c c' c^2 and c^3 of the groups of apparatus C. A conductor l^3 , connected to the conductor l^2 , leads to the corresponding terminals in the apparatus C' located on the other side of the track. As a train moves along the track the contact devices in the two blocks ahead have been set by it so as to give an approaching train a red signal, while in the two blocks in rear these devices have been set to give a following train a green signal. As a train passes onto a new block it first disconnects the contact devices for giving the signal, which were previously connected by itself in that block, so that the engineer will not receive his own signal, and at the same time connects the contact devices for actuating a signal in a train in the second block ahead so that signals are always maintained in two blocks ahead of the train. Suppose a train moving to the left runs onto block 6 in Fig. 1, then the actuating rod d^6 on the right

hand side of the locomotive strikes the circuit closing device D. The middle contact spring of this device is connected to the negative side B' of the line, as explained before, by the conductor l' , while one of the other terminals is connected to a conductor l^4 which goes to the magnet c^3 and through conductor l^2 to the positive side of the line, which causes this coil to attract its armature and release the switch c^5 , thus opening the circuit which connects the contact devices F and F' to the supply wires B and B', as explained before. The other conductor l^5 from the device D goes to the second block ahead (in this case block 4) to the magnet c^2 which is connected to the positive side of the line by conductor l^4 , thereby closing the switch c^5 which connects the contact devices F F' in this block 4 to the supply wires, thus connecting contact devices to the supply line which will give a red light in an approaching train. As the train passes on it makes contact with the four contact devices F F' F² F³. The train will receive no signal from these devices since the contacts F F' have just been disconnected from the supply lines, as explained, and the contacts F² F³ are only energized after a train has passed over them in the opposite direction, viz. from left to right in Fig. 1, as will be shown later. Therefore, the train can receive no signals here and passes on to the contact devices E E' E² E³. If another train is approaching on the same track, the contacts E E' will be connected to the supply lines, as hereinafter explained, and the engineer will receive a red light in his cab. The contact devices E² E³ are connected to the lines B B' by a preceding train moving in the same direction, viz. from right to left in Fig. 1, just after it leaves the block 6 and they are left connected until the train has passed the second block ahead, when they are disconnected. If this preceding train is within two blocks the engineer on the train on block 6 will receive a green signal from the contact devices E² E³. If he receives neither red nor green signals, then he knows that the track is clear for two blocks ahead of him. The train next actuates the circuit closing device D' located near the end of the block. The middle conductor spring of the device D' is connected to the negative side of the line by conductors l' and l , while one of the other springs is connected by conductor l^6 through the magnet coil c^2 and conductors l^3 and l^2 to the positive side of the line which closes the switch c^5 , thereby connecting contact device E² through the switch c^5 and conductors l' and l to the negative side of the line, and the contact device E³ through the switch c^5 and the conductors l^3 and l^2 to the positive side of the line simultaneously, as previously explained for contact devices F² and F³, thus connecting the contact 130

devices to give a green signal in a train coming from behind. The third terminal of the circuit closing device is connected to conductor l^7 which leads to the magnet c^3 for the 5 second block in rear of the train, viz. block 8, the other terminal of this magnet being connected to the positive wire B by the conductors l^3 and l^2 for block 8, which will open a switch c^5 in that block and disconnect 10 from the supply line the contact devices E^2 E^3 , and thus break the connections for a green signal that were previously made by the train. The train then runs onto the next 15 block, engaging a device D and repeating the same operations in block 5 as were described for block 6, connecting and disconnecting the signal contact devices to and from the supply line, one block farther to the left. The dotted lines in block 6, Fig. 20 1, represent a locomotive moving toward the left and carrying the contact rings which are shown in engagement with the contact devices F F' F^2 F^3 , the arm d^6 having passed the circuit making device D of block 25 6. The contact devices F F' in the blocks 4 and 5 ahead of this train are shown connected to the supply lines by the switches c^5 in the two groups of apparatus C located near these blocks to give an approaching 30 train a red signal. In the two blocks 7 and 8 behind the train, the contact devices E^2 E^3 are also connected to the supply lines by the switches c^5 in the two groups of apparatus C', to give an approaching train a green 35 signal. For trains running in the opposite direction, viz., to the right in Fig. 1, the operations are the same as before described but are effected through the medium of the circuit closing devices located on the opposite 40 side of the track.

Briefly stated, the operations after the train runs onto a block are as follows: The circuit closing device D is actuated by a locomotive, closing a circuit from the negative side of the line to the middle conductor spring of the device which is connected to the conductor l and through the conductor m to the magnet c' , and to the positive side of the line through conductors l^3 and l^2 , 45 which opens the switch c^4 and disconnects the contact devices E E' from the supply lines. The other conductor m' from the device D goes two blocks ahead to a magnet c and to the positive side of the line through 50 conductors l^3 and l^2 , closing the switch c^4 in that block and thereby connecting the contact devices E E' to the supply wires. The train receives no signals from the contact devices E E' E^2 E^3 for the same reason that 55 a train moving in the opposite direction receives no signals from the contact devices F F' F^2 F^3 . Passing on to these last mentioned contact devices, the engineer will receive a green signal from the contact devices 60 F^2 F^3 if a preceding train is within the two blocks ahead, or a red signal from the contact devices F F' if an approaching train is within the two blocks ahead. Closing the circuits through the device D' causes current to flow from the negative side of the line 65 through conductor l to the middle conductor spring of this device and through conductor m^2 and magnet c to the positive side of the line through conductor l^2 , thereby closing the switch c^4 and connecting contact 70 devices F^2 F^3 to the supply wires. The third terminal of the circuit closing device is connected by a conductor m^3 to the switch releasing magnet c' in the second block in rear of the train, and to the positive side of the line by conductor l^2 , releasing the switch c^4 and disconnecting the contact devices F^2 F^3 from the supply wires B B'. The train 75 runs to the next block and the same operations are again repeated.

Briefly summing up, the operations for each block for trains moving in either direction are as follows: By actuating the device D at the beginning of each block the train disconnects the red signal contact devices previously connected by itself in that block and connects similar devices in the second block ahead, so that contact devices for two red signals are always connected ahead of it. By engaging the device D' just before 80 leaving the block, the train connects the contacts for giving a green signal behind itself in the block which it is about to leave, and also disconnects from the line contact devices for a similar signal in the second block 85 behind, so as to leave connections for displaying green signals in two blocks behind that occupied by the train. Trains moving to the right in the diagrams receive either red or green warning signals by means 90 of the contact devices F F' and F^2 F^3 , respectively, while those moving to the left receive corresponding warnings by means of the contact devices E E' and E^2 E^3 . A conductor n in each group of apparatus C and C' connects the negative terminals of the two adjacent releasing magnets c' and c^3 . Each pair of the magnets thus connected 95 releases the switches and breaks the connection between the supply wires and the four 100 contacts of each group of contact devices. By connecting the negative sides of the magnets together, as shown, both of these magnets are energized together and both release their switches c^4 and c^5 at the same time. 105 The purpose of this connection is as follows: When a train moves forward on the track the contact devices for two red signals are connected to the line in the two blocks ahead of it. Now if the train for 110 any reason moves out on the track a certain distance and then goes back the contact devices for the two red signals in the blocks ahead of the point at which the engine reversed its movement would ordinarily 115 120 125 130

be left connected to the line, but by connecting the two releasing magnets these devices are disconnected from the line, since on reversing the engineer lowers the arm depending from the left side of his engine and actuates the circuit closing devices D' which are connected to two blocks in rear of him (as regards the direction in which the train is then moving) to disconnect from the line the contact devices for the green signal. Since the releasing magnets for both the red and green switches are connected as stated, both switches c^4 and c^5 will be opened, thereby leaving the line clear for the next train. When a train runs onto the first block of the system (see Fig. 2), assuming it to be moving to the right, it engages the device D , completing a circuit from the negative side of the line through conductors l and m to the magnet c in block 3 and through conductors l^3 and l^2 to the positive side of the line, thereby closing the switch c^4 and connecting the contact devices E E' to the supply lines. This circuit is the same as for any of the intermediate blocks previously described. The other conductor o from the circuit closing device leads to a switch closing magnet c in the second block, the positive terminal of which is connected by the conductors l^3 and l^2 to the supply lines, whereby the contact devices E E' in that block are connected to the supply lines. Hence by actuating the circuit closing device D in the first block, the contact devices for two red signals are connected to the line at one time by the train, in the two blocks ahead. By engaging the device D' near the end of the block, the contacts F^2 F^3 are connected to the supply lines, as was explained before. Since there is no green signal in rear of the train to be disconnected, the other conductor of this circuit closing device is omitted. In block 2 the device D is connected in the same manner as that for the other intermediate blocks, while the device D' at the end of this block is connected in the same way as the device D' for block 1, one conductor being also omitted since there are no contact devices to disconnect in the second block behind. The connections for block 3 are complete and the same as for the other intermediate blocks. A train moving in the opposite direction operates successively the upper series of devices D and D' in Fig. 2. Running onto block 2 the train actuates the device D and closes a circuit in the same manner as before described from the negative side of the line through conductors l and l' , device D , conductor l^4 , magnet c^2 and conductor l^3 to the positive side of the line, thereby disconnecting the contact devices F F' from the supply circuit. Since no contacts have to be connected for a red signal in the second block ahead, the other

conductor leading from the device D is omitted. The device D' at the end of this block is connected as in any intermediate block for connecting contact devices to actuate a green signal in a train in block 2 and disconnecting the contact for a green signal in the second block in rear. Device D in block 1 is connected in the same manner as device D in block 2, merely disconnecting the contact devices F F' in block 1 from the line. A train about to leave the last block 1 must disconnect the contact devices for actuating the green signals in two blocks in rear of the train, and accomplishes this by actuating the device D' , thereby closing a circuit through conductors l , l' and l'' , magnet c^3 in block 3, and conductors l^2 and l^3 to the positive side of the line, opening switch c^5 and disconnecting the contact devices E^2 E^3 from the source of supply, in the same manner as described for the other blocks. The other circuit is completed by conductor o' to the releasing magnet c^3 in block 2, thus opening the switch c^5 and disconnecting the contacts E^2 E^3 from the supply wires. All the contact devices are then disconnected behind the train.

In the foregoing description the signals displayed in the locomotive were assumed to be red and green lights, but this invention is not limited to these signals, since any kind of visible or audible signaling device may be used to warn the engineer and enable him to distinguish between the signals given by an approaching or by a preceding train. The actuating rod d^6 and the contact devices G are described as being attached to parts of the locomotive or tender, but these parts may equally well be located on any part of a train or on an electrically operated car.

The system described has a number of advantages. Enough signals are given to the engineer to warn him of the presence of trains in front of him and of the direction of their movement without unnecessarily complicating the system. The apparatus and connections are simple in construction and are not liable to get out of order in any way, but if one of them should fail to operate, the warning will be given by a second one. If desired, signals may be actuated in trains in three or more blocks ahead or behind the train by merely leading the connections to the third or other block ahead or in rear instead of at the second block, as described, which will act as an additional safe guard. Another advantage is that no parts connected to the supply lines are exposed on the track, making the tracks safer for persons walking thereon and also eliminating the possibility of disarranging the system by accidentally short-circuiting some of the current carrying parts. The system requires very little attention, which reduces the expense of maintenance. The power required

to operate the system is small, since the current is only used during short intervals of time. If the track is clear, the local train carried circuit is not in use at all, and when 5 in use, it is only closed long enough to warn the engineer. It is not necessary to use the rails as conductors and to bond them, nor to insulate them and divide them into blocks. Thus the system can be used equally well on 10 steam or electrically operated railroads.

I claim as my invention:

1. In a railway signal system, the combination of a source of current supply, circuit closing devices adapted to be actuated by a 15 passing train, an electromagnet for each circuit closing device adapted to be momentarily energized from said source of current supply when the corresponding one of said circuit closing devices is actuated by a train, 20 a partial circuit, switches in said partial circuit adapted to be closed by said electromagnet for connecting said partial circuit with said source of current supply, means for releasably holding said switches closed, 25 contact devices located at intervals along the track and forming the terminals of said partial circuit, and a partial circuit on the train including signaling devices and contact devices adapted to engage with said contact 30 devices on the track for causing a momentary current from said source of supply to actuate said signaling devices, substantially as set forth.

2. In a railway signal system, the combination of a source of current supply, circuit closing devices adapted to be actuated by a passing train, an electromagnet for each circuit closing device adapted to be momentarily energized from said source of current 35 supply when the corresponding one of circuit closing devices is actuated by a train, a partial circuit, switches in said partial circuit adapted to be closed by said electromagnet for connecting said 40 partial circuit with said source of current supply, means for releasably holding said switches closed, contact devices located at intervals along the track and forming the terminals of said partial circuit, a partial 45 circuit carried by said train including contact devices adapted to engage said contact devices on the track for causing a momentary current to flow in said partial circuits from said source of current supply, and a relay 50 circuit including a signaling device on the train adapted to be completed by said train carried partial circuit for actuating the signal device in the train, substantially as set forth.

3. In an electric signal system, the combination of a source of current supply, circuit closing devices located along the track and adapted to be actuated by a passing train, contact devices which are located at 55 intervals along the track, conductors including

switches for connecting said contact devices to and disconnecting them from said current supply, and a partial signal circuit carried by the train and including signals and conducting parts adapted to engage said contact 70 devices, the alternate circuit closing devices being similarly connected to operate said switches, one of said circuit closing devices being adapted to connect to the current supply contact devices located a distance ahead 75 of the train and disconnect from the current supply similar devices located a shorter distance ahead of the train, and the next adjacent circuit closing device being adapted to connect to the current supply contact devices 80 located a short distance behind the train and disconnect from the current supply similar devices located a greater distance behind the train, whereby contact devices located a certain distance ahead of and in rear of the 85 train are maintained in connection with the supply line to transmit signals to approaching trains, and whereby contact devices located in proximity to said train are disconnected from said current supply to prevent 90 the train from receiving signals from contact devices connected to the current supply by itself, substantially as set forth.

4. In a railway block signal system, the combination of a source of current supply, 95 contact devices in each block, circuit closing devices adapted to be actuated by a passing train, controlling means for each block governed by said circuit closing devices, connections between the first of said circuit closing 100 devices of the system and each of said controlling means in a predetermined number of blocks ahead of said first device for connecting to the source of supply the contact devices in said predetermined number of 105 blocks ahead of the first mentioned device, connections between each circuit closing device after said first device and the controlling means in a block a predetermined number of blocks ahead for connecting to the 110 source of supply contact devices in said block, and connections between each of said circuit closing devices and the controlling means in the block next ahead for disconnecting the contact device in said block from 115 the source of supply, substantially as set forth.

5. In a railway block signal system, the combination of a source of current supply, contact devices in each block, circuit closing 120 devices adapted to be actuated by a passing train, controlling means for each block governed by said circuit closing devices for connecting and disconnecting said contact devices to and from the current supply, connections between each of said circuit closing devices except the last device of the system and the controlling means in a block in rear of the device for connecting with the source 125 of supply contact devices in said block, con-

nctions between each of said circuit closing devices and the controlling means in a block a predetermined number of blocks in rear of the device for disconnecting from the 5 source of supply contact devices in said block, and connections between the last of said circuit closing devices of the system and each of said controlling means in a predetermined number of blocks in rear of said 10 last device for disconnecting from the source of supply the contact devices in said predetermined number of blocks in rear of said last device, substantially as set forth.

6. In a block signal system, the combination of a supply line, contact devices arranged in groups of four at intervals along the track, conductors including switches for connecting the diagonally opposite pairs of said contact devices to the supply line, 15 means actuated by a passing train for operating said switches, a group of conducting parts on the train corresponding in arrangement to and adapted to engage the several contact devices of each group on the track, 20 and partial signal circuits on the train each of which is completed through diagonally opposite contact devices and conducting parts, whereby different signals are actuated in the train by currents from different pairs 25 of contact devices, substantially as set forth.

7. In an electric block signal system, the combination of a source of current supply, contact devices arranged in groups along the track each group consisting of a plurality of pairs, conductors including switches for connecting pairs of said contact devices to the current supply, co-acting contacts and electrical connections carried by the train whereby different signals are actuated in the 30 train from different pairs of contact devices of said groups, closing means and opening means for said switches, devices which are actuated by the train and are connected to operate said means, and connections between 35 said switch opening means whereby all contacts of each of said groups are adapted to be disconnected from the line together, substantially as set forth.

8. In an electric block signal system, the combination of a source of current supply, contact devices on the track arranged in two pairs adjacent to each other, conductors including switches for connecting said pairs of contact devices to the current supply, co-

acting pairs of contacts on the train and 55 means whereby different signals are actuated from different pairs of contact devices, closing and releasing magnets for said switches, circuit closing devices which are connected to operate said magnets, and a 60 connection between said releasing magnets whereby said magnets are both energized at the same time to disconnect the contact devices from the current supply, substantially as set forth.

9. In an electric block signal system, the combination of a supply line, two series of circuit closing devices adapted to be actuated by trains moving in one direction, a series of contact devices, connections including switches and switch operating means for connecting said contact devices to said supply lines, said switch operating means being controlled by said circuit closing devices, partial signal operating circuits carried by the train and having parts adapted to engage with said contact devices and which are adapted to conduct a current from said contact devices to actuate a signal on the train, said circuit closing devices of the 70 first series being each connected to open a switch to disconnect from the line a pair of contact devices located in the same block a short distance ahead and to close a switch which connects to the line a pair of contact 75 devices located on the track a certain number of blocks ahead, and said circuit closing devices of the second series being each connected to close a switch which connects to the line a pair of contact devices located in the same block a short distance in rear, and to open a switch to disconnect from the line a pair of contact devices located a certain number of blocks in rear, a second set of contact devices and two series of circuit 80 closing devices which are connected to co-operate with said contact devices and with trains moving in the opposite direction similar to said first mentioned contact devices and circuit closing devices, substantially as 85 set forth.

Witness my hand in the presence of two subscribing witnesses.

ADOLF PILLICH.
